(57) **CLAIM**

The ornamental design for the automotive plug, as shown and described.

DESCRIPTION

FIG. 1 is a perspective view of my automotive plug in accordance with my invention;

FIG. 2 is a bottom view thereof;

FIG. 3 is a top view thereof;

FIG. 4 is a side view thereof;

FIG. 5 is an opposing side view thereof;

FIG. 6 is a front view thereof; and,

FIG. 7 is a rear view thereof.

The broken line portion of the figure drawings is included to show portions of the article that form no part of the claimed design.
